(57) **CLAIM**

The ornamental design for a shoe, as shown and described.

DESCRIPTION

The file of this patent contains at least one drawing/photograph executed in color. Copies of this patent with color drawing(s)/photograph(s) will be provided by the Office upon request and payment of the necessary fee.

1. Shoe

Fig. 1.1 is a front side elevational view of a shoe showing the claimed design;

Fig. 1.2 is a rear side elevational view thereof; and

Fig. 1.3 is a top plan view thereof.

The broken lines define the boundary of the claimed design and form no part thereof. Although shown in the context of a shoe for the left foot, an embodiment of the present invention may be incorporated in a shoe for the right foot.
